FREDERICK A. STEVENSON, OF DETROIT, MICHIGAN, ASSIGNOR TO AMERICAN CAR AND FOUNDRY COMPANY, OF ST. LOUIS, MISSOURI, A CORPORATION OF NEW JERSEY.

CAMBER-PUNCHING DEVICE.

1,164,026.

Specification of Letters Patent. Patented Dec. 14, 1915.

Application filed February 10, 1914. Serial No. 817,797.

To all whom it may concern:

Be it known that I, FREDERICK A. STEVENSON, residing at Detroit, Michigan, and being a citizen of the United States, have invented certain new and useful Improvements in Camber-Punching Devices, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a front elevation of the camber punching device, the guide and templet being shown in section. Fig. 2 is a view similar to Fig. 1, but in vertical section. Fig. 3 is a horizontal section along the line 3—3 of Fig. 1. Fig. 4 is a vertical section along the line 4—4 of Fig. 1, looking in the direction of the arrows, and showing roller supports for the guide, templet and work. Fig. 5 is a detail sectional view along the line 5—5 of Fig. 1, through the top plate and one of the punch blocks, showing the gag in position to render the punch operative; and Fig. 6 is a detail of the templet indicator.

Among the various types of railroad cars will be found those of considerable length, whose longitudinal sills, center and side, are designed to resist the tendency of said sills to sag within the portion located between the bolsters, by being provided with a camber.

The present invention has to do with a device for conveniently and economically punching the holes paralleling the camber of the sill, and in the operation of the machine herein described this is in conjunction with whatever other punching operations are required upon said sill. This eliminates an extra operation hitherto necessary because of the arcuated path of the camber paralleling holes, it being evident that with a straight feeding of the work to the punches, a set punch would intersect the center line of the camber paralleling holes at only two points, *i. e.*, at each extremity of the curved center line.

With the device herein described set up in a multiple punch, if any gang of punches

be set up in connection with it, a smooth uniform advance of the work through the multiple punch can be secured, and, upon the completion of the advance of the work, all holes to be punched in the sill, including those which are in juxtaposition to the cambered edge will have been produced with a single passage of the work.

The cambering device is illustrated in the drawings accompanying and forming part of this specification, but it has been deemed unnecessary to illustrate a gang of set up punches as this is an old and common practice, and forms no part of the present invention, except in that it may, and often will, be found desirable to operate my device in connection with one of the countless set ups possible in a gang of punches.

Referring now to the drawings, 1 indicates the web for a built-up center sill, sheared from commercial plate, shown in dot and dash lines, it being noticed, that in the form of the device shown, two such webs may be operated upon at the same time. It is, of course, obvious that the device may be modified to operate upon but a single web or plate, or, on the other hand, upon a greater number than two.

The plates 1 are from time to time advanced in a well known manner moving over the bottom plates 2 which constitute guides for the sliding die blocks 3. Reference to Fig. 3 will disclose short intersecting lines or crosses in proximity to the cambered edges of plates 1. These intersections represent the location of holes to be punched. By a further scrutiny of said figure there will be observed a longitudinally movable templet 4 carried by a longitudinally movable punch guide 5, said templet being provided with transverse graduations 6. The longitudinal spacing of the graduations just referred to agrees with the spacing of the holes in plates 1, as indicated by the crosses, though, it is to be understood, the crosses are not placed on the plates in reality, being employed in the drawing simply as an aid to description. By reason of not having to mark the location of the holes on the plate considerable time is saved, particularly where a great number of plates are to be operated upon.

An indicator 7 is employed in connection with the graduations 6 upon the templet 4, and is in the form of a cylindrical rod pro-

vided at its upper end with a head and being beveled or chisel-shaped at its lower end. Said indicator is held in suspension by a block 8, located and secured in a T-shaped slot 9 in the top plate 10, the latter being bolted to the slide 11 of the multiple punch.

Whenever the plates 1, templet 4 and guide 5 are advanced, they move in unison until one of the graduations 6 comes underneath the beveled or pointed end of the indicator 7, whereupon an attendant causes the forward movement of the plates, templet and guide to cease, it being then known that the location for a hole in each plate 1 is in alignment with its respective punch 12, carried by its associated punch block 13, the latter being slidably retained in the T-slot 9 of the top plate 10.

Upon the downward thrust of the slide 11, the punches 12 will descend, and, penetrating the webs or plates 1, enter their dies 14. After the upward or return stroke of slide 11, and, consequently the punches, the guide 5, with the templet 4 and the plate 1 will be again advanced until the next of the graduations 6 comes beneath indicator 7, whereupon the parts just mentioned are again brought to rest with the location of the center of the next hole to be punched in each plate in coincidence with the centers of its respective punch and die.

In Fig. 3, the central portion of webs or plates 1 are shown, and at the middle for a short distance the holes to be punched are in a straight line, in this particular instance. The camber is apparent each side of this short middle portion. Now, it will be noticed that the sides of the guide 5 are parallel to the cambered edges of plates 1 and change their direction in accordance with the contour of said plates. As rollers 15, which are rotatably mounted upon vertical pintles 16, the latter having a driving fit in die blocks 3 and extending upwardly into cylindrical holes in the punch blocks 13 of substantially the same diameter as the pintles themselves, are spring pressed at all times against the sides of the guide 5, they must respond to all changes of direction of the said sides of guide 5. This being so, as the sides of guide 5 follow the camber of the plates or webs 1, the rollers 15 are compelled to do likewise, and, because of the rollers' pintles being connected to the punch blocks 13 and die blocks 3, the punches 12 and their dies 14 also follow the outline of the camber along the imaginary center line upon which the desired holes are to be punched. The action of guiding the punches and their dies is thus automatically accomplished, leaving the attendant or operator free to control the longitudinal spacing of the holes as regulated by the templet, and also to operate the multiple punch to cause the downward stroke of the slide 11, which, as

before stated results in carrying down the punches, through the plates or webs 1, into their dies.

Means for spring pressing the rollers 15 against the sides of the guide 5 consist of two rectangular bars 17, each surrounding and carried by one of the pintles 16, the ends of these bars being bent into a slightly higher plane and presenting a point of attachment for springs 18, and these springs themselves. Thus are the rollers drawn toward each other, being kept separated by the guide 5 alone, the varying widths of said guide resulting in the actuating of the rollers 15 to move the punches and their dies across the surfaces of the plates 1.

While passing through the camber punching device, the guide 5 is restrained from lateral movement by having an angle 19 depending from said guide, and secured thereto, pass between two rollers 20, the latter being mounted upon studs 21. The studs are secured into a plate 22, which is in turn secured to body 23 of the multiple punch.

Each punch block 13, which slides in the T-shaped slot 9 of the top plate 10, is provided with a gag 24 for rendering its respective punch either operative or inoperative. Attached to each gag is a handle 25 for actuating it. Reference to Figs. 1, 2, 4 and 5 clearly show the gags and their relation to the punches, and in Fig. 1 the top plate will be found to possess slots 26 which accommodate the outwardly projecting ends of the gags as the latter are moved transversely when the punch blocks travel partially across the face of the plate 1 as the result of the action of the guide 5 and rollers 15.

As seen in Fig. 2 at the left and also in Fig. 5, when the gag is pushed inwardly, the space above the stem of punch 12 is occupied by said gag, and, therefore, when slide 11 moves downwardly said punch is carried with it to perform its work. When, however, said gag is pulled out so as not to be at all present over the punch stem the vacant space above said punch stem permits the stem to recede into this space to an extent sufficient to keep the punch 12 from penetrating the plate 1.

The operation of the device is as follows: Two webs or plates 1 are set into place in the usual manner, and are controlled by mechanism not shown, but thoroughly understood in the art, so as to be capable of being fed forwardly from time to time and to the extent desired, at the will of the operator. The forward advance of the plates 1 is accompanied by a corresponding travel of the guide 5 and the templet 4. As the first graduation on the templet comes underneath the indicator 7, the plates 1, guide 5 and templet 4 are brought to rest. Grasping

the gag handles 25 the operator pushes the gags 24 in over the stems of punches 12 and causes the slide 11 to descend, whereupon a hole is punched in each of the plates 1.

- 5 After the slide 11 has risen to its normal position, the plates 1, guide 5 and templet 4 are again advanced until the next of the graduations 6 comes under the indicator 7, when the advance is stopped and the 10 punching operation is repeated, and so on. Now, if the camber on the plates is progressing to increase the width of the plate, the width of the guide 5 will be less than it was when the first holes were punched in 15 plates 1, and, under the action of springs 18, the rollers 15 will draw nearer to each other as permitted by the narrowing of the guide 5. It being borne in mind that the contours of the guide 5 and the camber of plates 1 20 correspond, it will be seen that the distance each roller 15 moves in toward the other agrees with the amount of space that the second hole is displaced laterally from the first. And throughout each longitudinal 25 step or movement of the plates 1, guide 5 and templet 4, the movement of the rollers 15, controlled by guide 5, coincides in the same way with the lateral displacement of the holes to be successively punched in the 30 plates.

The rollers 15, surrounding pintles 16, force the latter with them inwardly or outwardly according to the curvature or outline of guide 5, and the pintles being attached to the punch blocks 13 and die blocks 3 cause them to also move with the pintles an amount equal to that which the rollers 15 caused said pintles to move. Of course, with the punch and die blocks, punches 12 40 and dies 14 move the same distance as the former were moved by the pintles. And, therefore, the curvature or outline of the guide 5, agreeing with the curvature or outline of the camber, and the punches and dies, 45 12 and 14, respectively, moving in synchronism with the rollers 15, which closely follow the outline of guide 5, a series of holes is punched in plates 1 which is parallel to the outline of the camber of said plates.

50 What I claim is:—

1. In an automatically controlled punching device, a plurality of punches and dies, longitudinally movable means for automatically moving each punch and its die transversely of the work to varying lateral positions thereof, means for regulating the advance of said work through said machine, and means for operating said punches.

2. In an automatically controlled punching device, a plurality of punches and dies, longitudinally movable means for automatically moving each punch and its die transversely of the work to successively varying lateral positions thereof, said 65 punches and dies being positioned on oppo-

site sides of said automatic means, means for regulating the advance of said work through said machine, and means for operating said punches.

3. In an automatically controlled punching device, a plurality of punches and dies, a longitudinally movable punch-guide and means co-operating therewith adapted to automatically position each punch and its die transversely of the work, means for regulating the longitudinal advance of said work, guiding means for said automatic means, selective means for rendering any punch operable, and means for operating a selected punch or punches. 70

4. In a punching device, a plurality of punches and dies, supporting members therefor adapted to slide transversely of the work, devices for maintaining each punch supporting member in alinement with its associated die supporting member, and for synchronizing the sliding movement of both, longitudinally movable means for actuating said devices to cause said punches and dies to automatically move transversely 90 of said work, means for regulating the longitudinal advance of said work, selective means for rendering any punch operable, and means for operating selected punches. 85

5. In a punching device, a plurality of 95 punches and dies, slidable supporting members therefor, guiding and retaining members for said supporting members, devices for maintaining the alinement of associated punch and die supporting members and 100 for automatically imparting synchronous transverse movement to said supporting members with relation to the movement of the work and longitudinally movable means for actuating said devices to cause said 105 punches and dies to move to successively varying positions transversely of said work.

6. In an automatically controlled punching device, slidable punch and die supporting members, a punch carried by the former 110 and a die by the latter, a pintle secured to said die-supporting member, a roller mounted on said pintle, means impinged against by said roller, said means being adapted to move said roller to successively 115 varying positions, whereby said punch and die are correspondingly moved transversely of the work, means for regulating the advance of said work under said punch, and means for operating said punch at will. 120

7. In an automatically controlled punching device, a couple of oppositely movable die-supporting members, a die in each, and each carrying a pintle, a couple of oppositely movable punch supporting members 125 each carrying a punch, and each engaged by one of said pintles and adapted to slide telescopically thereon, a roller mounted on each pintle, means engaged by each roller adapted to move the latter to successively 130

varying positions, whereby said punches and dies are correspondingly moved transversely of the work, means for regulating the advance of said work, means for rendering either or both punches operable and means for operating operative punches.

8. In an automatically controlled punching device, a couple of oppositely movable die-supporting members, a die in each, and 10 each carrying a pintle, a couple of oppositely movable punch supporting members each carrying a punch, and each engaged by one of said pintles and adapted to slide telescopically thereon, a roller mounted on 15 each pintle, a guide, each of whose sides is a developed cam of the same outline as a path of changeable direction in which holes are to be produced, spring pressed means for maintaining said rollers in contact with the cam sides of said guide, a longitudinal spacing templet carried by said guide and an indicator co-acting therewith whereby the advance of said work may be regulated, means for directing the movement of said guide, means for rendering either or both punches operable, and means 25 for operating operative punches.

9. In combination in a punching machine, a punch and a die, a longitudinally movable 30 templet and punch guide and means operating with said guide adapted to automatically shift the positions of said punch

and die during longitudinal movement of the templet.

10. In combination in a punching machine, a longitudinally movable punch guide having a side predetermined contour, a movable punch and die and means bearing on the side of said guide and connected to and connecting said punch and die adapted 40 to automatically move said punch and die transversely of the path of travel of said punch guide.

11. In combination in a punching machine, a longitudinally movable punch guide 45 of variable width, punches movable transversely of the path of travel of said punch guide and resilient means connecting said punches adapted to bear on said guide.

12. In combination in a punching machine, a longitudinally movable punch guide, means for preventing lateral movement of said guide, a punch movable transversely of the path of travel of said guide, a 50 yieldingly held roller adapted to bear on said guide and means connecting the roller and said punch adapted to synchronize their movements.

In witness whereof I have hereunto set my hand in the presence of two witnesses.

FREDERICK A. STEVENSON.
